(76) Inventor: **Robert Rose**

The United States of America.

TO ALL TO WHOM THESE Letters Patent shall come

Whereas Robert ... of ...
the United States, hath alleged that he has invented a new and useful improvement
... in the art of ... for the manufacture of ...

which improvement he states has not been known or used before his application; hath also alleged that he does verily believe that he is the true inventor or discoverer of the said improvement; hath paid into the treasury of the United States the sum of thirty dollars, delivered a receipt for the same, and presented a petition to the Secretary of State, signifying a desire of obtaining an exclusive property in the said improvement, and praying that a patent may be granted for that purpose; These are therefore to grant, according to law, to the said ... his heirs, administrators or assigns, for the term of fourteen years, from the ... day of ... one thousand eight hundred and ... the full and exclusive right and liberty of making, constructing, using and vending to others to be used, the said improvement; a description whereof is given in the words of the said ... himself, in the schedule hereto annexed, and is made a part of these presents.

In Testimony whereof, I have caused these Letters to be made Patent, and the Seal of the United States to be hereunto affixed.

6 1 7 R. S. under my hand, at the City of Washington, this ... day of ... in the year of our Lord one thousand eight hundred and ... and of the independence of the United States of America the forty

John Quincy Adams

BY THE PRESIDENT

John Quincy Adams

Secretary of State.

At Washington, To Wit

I do hereby certify, That the foregoing Letters Patent were delivered to me on the ... day of ... in the year of our Lord one thousand eight hundred and ... to be examined; that I have examined the same, and find them conformable to law, and I do hereby return the same to the Secretary of State, within fifteen days from the date aforesaid, to wit on this ... day of ... in the year aforesaid.

Attorney General of the United States.

The Schedule referred to in these Letters Patent and making part of the same, containing a description in the words of the said Robert Rose himself of his improvement in the machine for cutting tracks for gun carriages and for other purposes.

This machine may be made of brass, or any other kind of metal, and is formed in the following described manner.

Two circles or hoops of metal, of adequate thickness, and from twenty one inches diameter, to any other size, either more or less, according to the dimensions of the track required, form the outward sides of the machine. The two circles are placed opposite to each other, about nine inches apart, by four horizontal bars of the same metal, and equidistantly placed, all of which are cast together, and form one piece, being the outward part of the machine.

On the four horizontal bars are placed the bits that perform the operation of a wing; these bits are formed with a slot similar to some scissile scissars, capable to be regulated at pleasure by screws. Four or more of said bits are horizontally the cutting part appearing through perforations on the outside surface of the metal circle, that forms the frame of the machine.

In the center of the above described circles are placed the center part of the machine, which is also made of metal, and in appearance like an open cylinder, having a rim at the top of about six inches in diameter, or any other size that may be required. Said center part is depth as necessarily the same as the outward part of the machine, and has the same number of bits placed to it with the outward circles. The said center part is cast separately from the outward part, and is made to cut the sides of the track that receives the axle tree of the carriage.

The above described castings are placed by screws on four arms of iron, which form a cross, having a long female screw on the center for

for the purpose of dressing the machine to a mandrel, similar to a turner's lathe.
This machine can be put in motion, either by steam or animal
power.
